CLAIM

The ornamental design for a bag, as shown and described.

DESCRIPTION

FIG. 1 is a perspective view of a first embodiment of the design for a bag;

FIG. 2 is a front view of the first embodiment of the design for the bag;

FIG. 3 is a detail view of the pattern from the section indicated in FIG. 2 and FIG. 12;

FIG. 4 is a back view of the first embodiment of the design for the bag and also a back view of a second embodiment of the design for a bag;

FIG. 5 is a right side view of the first embodiment of the design for the bag and also a right side view of a third embodiment of the design for a bag, with the left side view of each embodiment being a mirror image of the right side view;

FIG. 6 is a top view of the first embodiment of the design for the bag;

FIG. 7 is a bottom view of the first embodiment of the design for the bag and also a bottom view of the second embodiment of the design for a bag and also a bottom view of the third design for a bag;

FIG. 8 is a detail view of the pattern from the section indicated in FIG. 5;

FIG. 9 is a perspective view of the second embodiment of the design for the bag;

FIG. 10 is a right side view of the second embodiment of the design for the bag, with the left side view being a mirror image of the right side view;

FIG. 11 is a top view of the second embodiment of the design for the bag;

FIG. 12 is a front view of the third embodiment of the design for the bag;

FIG. 13 is a back view of the third embodiment of the design for the bag; and,

FIG. 14 is a top view of the third embodiment of the design for a bag.

The pattern depicted in FIG. 8 is fragmentarily shown in FIGS. 1, 5, 6, and 14 for convenience of illustration. It should be understood that the pattern of FIG. 8 is continuous on the surfaces of the individual sections of the bag on which

(Continued)

it is depicted in FIGS. 1, 5, 6, and 14, and the pattern of FIG. 8 is not found elsewhere on the first embodiment of a design for a bag. It should be understood that the pattern of FIG. 3 is continuous on the surfaces of the individual sections of the bag on which it is depicted in FIGS. 1, 2, and 12, and the pattern of FIG. 3 is not found elsewhere on the first embodiment or third embodiment of a design for a bag.
